VARIABLE OUTPUT PUMP

Hallvard Naess, deceased, late of Jeloy pr. Moss,
Norway, by Hjordis Naess, administratrix,
Jeloy pr. Moss, Norway

Application November 24, 1948, Serial No. 61,803

4 Claims. (Cl. 103—161)

1

The present invention relates to a rotary fluid pump.

The principal object of this invention is to provide a pump of simple and inexpensive construction designed for high pressure, high efficiency and a simple and easy adjustment of the pump output.

Another important object of my invention is to provide a rotary pump which is continuously adjustable from zero to maximum output.

The invention will be subsequently described with reference to the accompanying drawing in which:

Fig. 1 shows, in cross section, a pump according to the invention, the section being taken on line 1—1 of Fig. 2;

Fig. 2 is a longitudinal section taken on the line 2—2 of Fig. 1;

Fig. 3 illustrates a modification, one half being shown in end view and the other in cross section;

Fig. 4 is a fragmentary longitudinal section of the pump shown in Fig. 3; and

Fig. 5 shows, in cross section, a double-action pump according to the invention.

For the purpose of illustration and to make the principle and operation of the present invention more readily understandable Figures 1 and 2 illustrate a simplified embodiment of my invention while Figures 3, 4 and 5 show an embodiment of my invention as it would be constructed in a practical design of same.

Referring to the drawing, there is indicated at 1 a pump housing having a cylindrical bore 2 wherein there is rotatably disposed a rotor 3 fitting snugly into the bore. The rotor is provided with gudgeons 4 rotatably journaled in end members 5 which are secured to the end faces of the pump housing 1. One of the gudgeons 4 may be coupled with a suitable source of power (not shown) for operating the pump.

The concentrically mounted cylindrical rotor 3 is provided at its periphery with a plurality of axially disposed channels 6, of suitable width and depth, each channel having parallel side walls and extending over the entire length of the rotor. There are four channels shown in the illustrated form of the invention being distributed about the periphery of rotor 3, yet it will be obvious that but a single channel or any convenient number thereof may be provided.

In each channel 6 there is arranged a plate-like pumping element 7 the length and width of which corresponds to that of the channel 6 so that the latter will be sealed off thereby. The element 7 projects at each end into a cam groove

5 8 provided in the adjacent end member 5. The cam groove 8 is circular and has an eccentricity relative to the axis of the rotor 3 which corresponds to one-half the desired radial displacement of the pumping element 7.

The element 7 has, accordingly, a thickness corresponding to the width of the cam groove 8 and an arcuate cross section conforming to the curvature of the groove. Since the element 7, 10 as the result of its entrainment by the groove 8, will rotate slightly about its longitudinal axis while executing its radial movement in the channel 6, its sides have been given the form of cylindrical surfaces 7' which will always insure a fluid-tight lineal contact between the element 7 and the side walls of the channel 6.

The ends of the element 7 entering the cam groove 8 are further provided at each side with a tongue-like projection 7'' which abuts the end 20 face of the rotor and prevents the passage of fluid from the channel 6 into the cam groove.

In order to avoid the development of low or high pressure in the space adjacent the inner surface of an element 7, all the channels 6 communicate with one another at the bottom by suitable passages formed in the member 3, for example, by a circular recess 12 provided at one or both ends of this member.

The pump housing 1 is provided with an outlet and an inlet port 9 and 10, respectively, for the pumping fluid, these ports being separated from each other by radially aligned partitions 11 the thickness of which is at least equal to, but preferably somewhat greater than, the width of the peripheral channels 6 of the rotor.

Upon rotation of the rotor 3, for example, in a clockwise direction as viewed in Fig. 1, the pumping elements 7 will be positively controlled from the eccentric cam groove 8 so as to descend within channels 6 while passing the inlet port 10, thereby drawing fluid into these channels, and to rise in the channels while passing the outlet port 9, thereby forcing the fluid out of the latter port; this operation will be readily understood.

45 The above-described construction eliminates all complicated packing means inasmuch as the end member 5, wherein the cam groove 8 is provided, seals the ends of the channels 6; since the pumping element 7 is in the form of a plate with arcuate cross section, its ends can be guided directly in the cam grooves 8 while the cylindrical side faces 7'' insure an effective seal at the channel walls. The elements 7, because of their plate-like configuration, require but a rela-

tively short guide path with reference to the extent of their radial displacement.

When the cam grooves 8 are provided in the stationary end members 5, as described above, an adjustment of the pump's output will not be possible. In order to allow for such an adjustment, the cam grooves 8 may be arranged on a packing disc or member movably mounted at each end of the pump housing and adapted to execute either a translatory movement in a plane passing through the axes of the rotor and of the cam groove or a swinging movement about a point offset from the rotor axis, or to rotate about this axis. An embodiment of the last-mentioned type is illustrated in Figs. 3 and 4.

In these figures, too, there is shown a pump housing 1 having a bore 2, a rotor 3 and gudgeons 4. If the pump is designed for high pressure, the plate-like pumping elements 7 are provided with plane side surfaces in order to enlarge the seal at the channel walls. Furthermore the elements 7 are provided at each end with outwardly extending angle members 7a which tightly abut the end faces of the pump housing and of the rotor and are dimensioned so as to seal off the radially outlying portion of the associated channel 6 in any position of the pumping element. Similar angle members may also be provided on the aforescribed elements 7 with arcuate cross section. Since the elements 7 in Figs. 3 and 4 are incapable of rotating about their longitudinal axis, they are provided at each end with a pin 13 carrying a roller or slider 14 which engages the cam groove 8, the latter being provided in a cam disc 15 which is rotatably mounted on a respective gudgeon 4 and is enclosed by the adjacent end member 5. The cam disc has a boss 16 which projects through the end member and has fixed thereto a lever 17, 17', respectively.

The levers or arms 17, 17a, extending from the two ends of the pump, are rigidly interconnected and, when rocked about their pivot, cause the two cam discs at their two ends of the pump (only one shown) to rotate simultaneously and, thereby, to shift the eccentricity of cam grooves 8. The result thereof will be that the pumping elements 7, which with the pump set for maximum output stand in their outermost and innermost positions while moving past the partition 11 from the outlet to the inlet and from the inlet to the outlet, respectively, will no longer occupy these extreme positions while passing the partition but will be displaced therefrom in dependence upon this shift in eccentricity. A certain amount of fluid will therefore be returned from the outlet to the inlet while, simultaneously, the quantity of fluid carried from the inlet to the outlet will be reduced by a similar amount, the distance between two opposite pumping elements remaining constant at all times. Thus, the shifting of the eccentricity will result in a return of a quantity of fluid which will increase at the same rate as the quantity of the forward-moving fluid decreases, until the two quantities are equal and the output of the pump drops to zero.

Hence it will be possible, by displacing or rotating the members carrying the cam grooves, to vary the pump output in continuous manner from maximum to zero and thence to maximum in the opposite direction without reversing the sense of rotation of the rotor.

The plate-like shape of the pumping elements enables the pump to be adapted for double ac-

tion by a simple arrangement which is illustrated in Fig. 5.

In this embodiment, the rotor 3 is provided with an inner bore, thus forming a sleeve with through-going channels 6. (It will be understood that the portions of the rotor separated by these channels are held together by suitable means, as by having part of the rotor, not seen in Fig. 5, constructed in a manner similar to the rotor in Figs. 1 and 2.) The interior of the rotor is divided, by a stationary wall 18 aligned with the partitions 11, into two chambers 19 and 20 which communicate with the inlet 10 and the outlet 9, respectively, by way of respective ducts 21 and 22, as shown.

When, in this embodiment, the rotor 3 is rotated clockwise, the pumping elements 7 will at their inner surfaces draw fluid from the chamber 19 and force it into the chamber 20 while, simultaneously, drawing fluid from the inlet 10 at their outer surfaces and forcing the latter fluid into the outlet 9. It will be apparent that in this embodiment, too, there may be provided movable cam discs as hereinabove described.

What is claimed is:

1. A rotary fluid pump comprising a housing having an inlet and an outlet, a cylindrical rotor having a pair of gudgeons rotatably journaled in said housing, said rotor being provided with at least one axially disposed channel with parallel side walls extending over the entire length of said cylindrical rotor, a pair of normally stationary discs rotatably journaled on said gudgeons, respectively, and abutting respective end faces of said rotor, each of said normally stationary discs being provided with a circular groove facing the rotor and eccentrically arranged relative to said gudgeons, a plate-like pumping element snugly received in said channel and provided with portions which extend beyond said channel and are received in said grooves, said pumping element dividing said channel into two parts, one of said parts being arranged to communicate alternately with said inlet and said outlet upon rotation of the rotor, and actuating means for swinging said discs about said gudgeons so as to vary the output of said pump.

2. A rotary hydraulic pump comprising a housing having an inlet and an outlet, said housing having internally two opposing radial barriers 50 between said inlet and outlet and being open at both ends; a pair of end plates covering said open ends of said housing and being removably secured to same, said end plates having internally an annular groove facing said ends of said housing and extending outside the edge of the opening in same; a pair of flanged sleeves forming a bearing located one in each of said end plates and being rotatable in same with their flanges on the inside and their sleeves extending through said end plates, concentric with same and projecting a short distance outside said end plates, said flanged sleeves each having an annular cam groove in their inner faces, said cam groove being eccentric with said sleeves; a cylindrical rotor 55 being journalled in said bearings in said flanged sleeves and being rotatable in said housing, said rotor having a plurality of external longitudinal channels cut through the entire length of the cylindrical portion of said rotor, same also having internal channels communicating between said external ones; a plurality of pumping elements 60 located one in each of said external rotor channels and extending beyond same into said annular eccentric cam grooves in said flanged

sleeves, both ends of said pumping elements having anti-friction bearings rolling in said annular eccentric cam grooves, and levers fastened upon the outside ends of said flanged sleeves whereby the eccentricity of said annular cam grooves may be changed in relation to the axis of said rotor.

3. A rotary hydraulic pump of the character described in claim 2 in which said pumping elements have radially and outwardly extending flanges abutting the ends of said housing and in which said pumping elements with said flanges are rotatable around the axis of said rotor upon an eccentric orbit determined by the adjustable eccentricity of said annular eccentric cam groove in relation to said barriers.

4. A rotary hydraulic pump of the character described in claim 2 in which said pumping elements have radially and outwardly extending flanges abutting the ends of said housing and in

which said pumping elements with said flanges are rotatable with said rotor on an eccentric orbit in relation to the axis of the rotor, with said flanges sliding in said annular grooves in the inside faces of said end plates.
